RIM ATTACHING MEANS

Elbert L. Potter and Elmer D. Swenson, Davenport, Iowa, assignors, by mesne assignments, to Kelsey-Hayes Wheel Company, Detroit, Mich., a corporation of Delaware

Application July 30, 1945, Serial No. 607,780

4 Claims. (Cl. 301—11)

1

The invention relates to means for attaching tire holding rims to wheel bodies and of that type permitting of attachment in different offset positions.

It is the object of the invention to obtain a construction formed of sheet metal which has a high degree of rigidity with comparatively light weight.

It is a further object to obtain a construction which is braced in three planes perpendicular to each other thereby securing maximum rigidity against stresses in all directions.

It is a further object to obtain a construction in which the sheet metal blanks are formed by bending operations and without the necessity of drawing or stretching the metal.

Still further it is an object to obtain a construction which can be manufactured at low cost. With these objects in view the invention consists in the construction as hereinafter set forth.

In the drawings:

Fig. 1 is a cross section through the wheel rim and the attachment means therefor;

Fig. 2 is a side elevation of a portion of the rim and attachment means;

Fig. 2A is an enlarged section on line 2A—2A, Fig. 2;

Fig. 3 is a plan view of the sheet metal blank from which one member of the attachment means is formed;

Fig. 4 is a side elevation of the member formed from the blank;

Fig. 5 is a cross section on line 5—5, Fig. 4;

Fig. 6 is a plan view of a blank from which is formed another member of the attachment means;

Fig. 7 is a side elevation of the member formed from the blank of Fig. 6;

Fig. 8 is a cross section on line 8—8, Fig. 7;

Fig. 9 is a view similar to Fig. 1 showing a modified construction of attachment means secured to a wheel body;

Fig. 10 is a side elevation thereof;

Fig. 11 is a plan view of a blank for forming one of the members of the structure in Figs. 9 and 10;

Fig. 12 is a side elevation of the member formed from Fig. 11;

Fig. 13 is a cross section on line 13—13, Fig. 12;

Fig. 14 is a side elevation of another member forming the structure of Figs. 9 and 10;

Fig. 15 is a perspective view of the members shown in Figs. 12 and 14 in assembled relation to each other but unattached to the rim;

2

Fig. 16 is a plan view of a blank for forming a member of another modified construction;

Fig. 17 is a side elevation of the member formed of Fig. 16;

Fig. 18 is a view similar to Fig. 9 with the rim secured in offset relation to the wheel body.

Attachment means for vehicle wheel rims to the wheel body are subjected to stresses in all directions. Thus, there is, first, radial stress; second, torque stress in the plane of rotation; and, third, axial stress. These stresses which are in planes perpendicular to each other are variously combined and, consequently, the attachment structure must be sufficiently rigid to withstand all of these combinations. A structure formed from sheet metal can be readily fashioned by bending to extend in two planes perpendicular to each other but it is more difficult to extend it into a third plane perpendicular to the other two without drawing or stretching the metal. In our improved structure this is accomplished by the combination of two separately fashioned sheet metal blanks which in assembled relation brace the structure in all three planes.

25 In detail and as shown in Fig. 1, 10 is the tire rim which is shown of the type having a drop center 11, bead seats 12 and flanges 13. The rim attachment means comprises two members 14 and 15 which are respectively fashioned as shown in Figs. 3, 4, 5 and 6, 7, 8. The sheet metal blank 16 shown in Fig. 6 is of substantially oblong rectangular form but is provided with extensions 17 at opposite ends thereof which are of less width than the portion 16. There is also an oblong aperture 18 centrally through the blank. The portion 16 is then bent into a channel or U-shaped form and the portion 17 turned oppositely outward and fashioned to conform substantially to the arc of the inner face of the drop center portion 11. The blank shown in Fig. 3 is of T form having a stem portion 19 and a head portion 20. The stem portion is bent downward perpendicular to the plane of the portion 20, is return bent and again bent in the plane of the portion 20 to extend oppositely therefrom for an equal length. It is then bent to form a shoulder 21 and an outwardly and upwardly bent portion 22 terminating in a flange 23 which contacts with the underside of the beaded portion 12 of the rim. The head portion 20 of the blank is bent into an arc corresponding to that of the portion 17 of the member 15. The member 14 thus formed has an aperture 24 bored or punched through the adjacent plies of the return-bent portion 25. This member is then assembled with

the member 15 by inserting the portion 25 through the slot 18 and with the portion 20 overlying the portions 17. The assembled structure is then placed beneath the rim in the proper position, the flange 23 is secured by a rivet 26 to the bead seat 12 and the portions 20 and 17 are secured to the drop center 11 by rivets 27. This brings the shoulder 21 in alignment with the righthand side of the member 15 (Fig. 1) and the outer end of the portion 20 in alignment with the left-hand side of the member 15. To secure the rim to the wheel body, such as a disc 28, a bolt 29 is inserted through the aperture 24 and an aligned aperture in the disc with the head 30 of the bolt against the portion 25 and with a clamping nut 31 engaging the threaded portion of the bolt on the opposite side of the disc. The disc may be placed either to the left or the right of the assembly by merely reversing the direction in which the bolt 29 is inserted through the aperture 24. As shown in full lines, Fig. 1, the disc is to be left and is in the central plane of the rim. On the other hand, when it is placed to the right it will be offset to a distance equal to the axial dimension of the member 15. In either position both members 14 and 15 are clamped against the disc as the portion 25 constitutes a tie connection therebetween. This portion 25 also constitutes a brace between the opposite sides of the channel or U-shaped portion of the member 15 which takes care of all torque stresses. On the other hand, axial stresses are absorbed by the axially extending portions of the members 14 and 15 and radial stresses by the radially extending portions thereof. The rivets 26 and 27 securely attach the assembly to the rim.

With the modified construction shown in Fig. 9, a member 15a is similar to the member 15 but, as in Fig. 11, has portions 32 extending oppositely outward from the ends of the portion 16 and spaced from the portions 17. These extensions 32 have their outer end portions bent to form flanges 33 for attachment to the bead seat 12 of the rim, while the flanges formed of the portion 17 are secured to the drop center of the rim as previously described. The member 14a is formed with a return bent portion 25a and with oppositely extending portions 34 at its upper end, being in this respect similar to the member 14. However, the flanges on the head portion of the blank, Fig. 3, are omitted and also the portion which is attached to the bead seat. Thus, the member 14a is not directly attached to the rim but is clamped against the wheel disc in the same manner as the member 14. One advantage of this is that it can float into alignment with the member 15a requiring less exactness in its manufacture.

What we claim as our invention is:

1. Means for attaching a rim to a wheel body comprising an assembly of two elements, one of said elements being of channel form in cross-section having flanges extending laterally from the sides of the channel for attaching it to the rim with the channel extending transversely of the rim, the other element being of generally T-shaped form in cross-section and having the stem extending within and transversely of the channel and provided with a bolt aperture for attachment to the wheel body and the head ex-

tending longitudinally of the channel with one end substantially flush with the corresponding channel end to bear therewith against the wheel body and means for locking the stem to the base of the channel.

2. Means for attaching a rim to a wheel body comprising an assembly of two elements, one of said elements being of channel form in cross section having the base of the channel provided with an aperture and also having flanges extending laterally from the sides of the channel for attaching it to the rim with the channel extending transversely of the rim, the other element being of generally T-shaped form in cross section and having the stem extending within and transversely of the channel and into the aperture in the base of the channel, the stem being provided with a bolt aperture for attachment to the wheel body, the other element also having the head extending longitudinally of the channel with one end substantially flush with the corresponding channel end to bear therewith against the wheel body.

3. Means for attaching a rim to a wheel body comprising an assembly of two elements, one of said elements being of channel form in cross section having flanges extending laterally from the sides of the channel for attaching it to the rim with the channel extending transversely of the rim, the other element being of generally T-shaped form in cross section and having the stem extending within and transversely of the channel and provided with a bolt aperture for attachment to the wheel body and the head extending longitudinally of the channel with its ends substantially flush with the channel ends to bear therewith against the wheel body when located at either end of the channel and means for locking the stem to the base of the channel.

4. Means for attaching a rim to a wheel body comprising an assembly of two elements, one of said elements being of channel form and having the base of the channel provided with an aperture and also having flanges extending laterally from the sides of the channel for attaching it to the rim with the channel extending transversely of the rim, the other element being of generally T-shaped form in cross-section and having the stem extending within and transversely of the channel and into the aperture in the base of the channel, the stem being provided with a bolt aperture for attachment to a wheel body, said other element also having its head extending longitudinally of the channel with shoulders substantially in the planes of the opposite ends of the first mentioned element and with an extension portion beyond one shoulder for attaching it to the rim.
